(57) **CLAIM**

The ornamental design for a packet for viscous material, as shown and described.

DESCRIPTION

FIG. 1 is a front perspective view of a packet for viscous material showing the new design;

FIG. 2 is a front elevation view thereof;

FIG. 3 is a top plan view thereof;

FIG. 4 is a side view thereof;

FIG. 5 is the opposite side view thereof;

FIG. 6 is a rear elevation view thereof; and,

FIG. 7 is a bottom plan view thereof.
